UNITED STATES PATENT OFFICE.

NOAH REINGOLD AND MEYER REINGOLD, OF NEW YORK, N. Y.

SUCTION DEVICE FOR UNHAIRING MACHINES.

Application filed March 20, 1924. Serial No. 700,543.

To all whom it may concern:

Be it known that we, NOAH REINGOLD and MEYER REINGOLD, citizens of the United States, residing at New York, in the county 5 of New York and State of New York, have invented certain new and useful Improvements in Suction Devices for Unhairing Machines, of which the following is a specification.

10 This invention relates to an improvement in suction devices for unhauling machines.

In unhauling machines employing a rotary knife, no provision has been made for removing the dust, powders, and impurities 15 in the skins being treated, and as a result the atmosphere becomes filled with it, making it almost impossible for an attendant to remain for any length of time on the job on account of having to inhale the fine dust 20 and impurities.

This invention prevents all this, and consists in the application of a detachable suction device to a machine of this character employing a rotating knife.

25 The invention consists in a hood made of two parts hinged together, and of sufficient size to embrace and afford clearance for the rotating knife, the hood being so constructed that it encloses this knife and confines the 30 dust, powders, and impurities as the unhauling takes place, whence it is removed by suction, thus preventing the air from becoming laden and contaminated with the dust and impurities.

35 In the accompanying drawings:—

Fig. 1 is a front view;

Fig. 2 is a rear view;

Fig. 3 is a vertical section; and

Fig. 4 is an end view showing a slightly 40 modified form.

The hood is made in an upper and lower section 1 and 2, respectively, each of which is approximately in the form of a half cylinder. These sections 1 and 2 are connected by hinge 3 at their rear, and they are recessed at the center 4 to receive the shaft 5 which carries the rotating knife 6. 45

The lower section 2 has an open mouth 7, where the knives 6 and 8 come together in 50 the unhauling operation, and through this mouth 7 hair is drawn, the suction being applied through the discharge pipe 9 at the rear.

In this way the hair removed, and all 55 dust, powders, and impurities are immediately drawn off and disposed of, instead

of being permitted to fill the air as heretofore.

The bed knife 8 in machines of this character swings up and down to meet the rotating knife 6 with each complete revolution, and a flexible apron 10 of canvas or other material extends from the base of the bed-knife or some convenient point to the lower edge of the mouth 7 of the hood. In this 60 way, the opening through the mouth is of comparatively limited area, and the size of the opening through the mouth varies with the relative position of the rotating cutting-knife and the bed-knife. 65

For convenience in handling the hood, it has a handle 11 at the top, and the sections are held together when clamped around the shaft 5 by some simple form of spring-catch 12, as shown in Fig. 1. 70

The cover or hood is supported by brackets 13 on each end bolted to some rigid part of the machine.

While the construction shown in Figs. 1, 2 and 3 is preferred, a form of gate 14, such 80 as illustrated in Fig. 4 has been tried. This is in the form of a gate of some light material, such as sheet-metal or the like, hinged at 15, and held under tension by a spring 16 with its free edge resting upon the bed-knife 8 or the cam 17.

The foregoing results could be obtained without employing either apron 10 or gate 14. One or the other, however, is generally preferred. 90

We claim:

1. A device of the character described having side and end walls, a rotary knife mounted therein, said side and end walls having a cutout portion forming an open mouth through which the end of the rotary knife protrudes at this point during rotation, and a movable bed-knife which oscillates to meet the rotary knife. 95

2. A device of the character described having side and end walls, a rotary knife mounted therein, said side and end walls having a cutout portion forming an open mouth through which the end of the rotary knife protrudes at this point during rotation, a movable bed-knife which oscillates to meet the rotary knife, and means actuated and controlled by the bed-knife for partially closing said mouth. 105

3. A device of the character described having side and end walls, a rotary knife mounted therein, said side and ends walls

- having a cutout portion forming an open mouth through which the end of the rotary knife protrudes at this point during rotation, a movable bed knife, and flexible means
- 5 extending from the bed knife to the lower edge of the mouth for partially closing said mouth.
4. A device of the character described including upper and lower sections hinged together and having an open mouth formed therein, a rotary knife mounted within the device, a movable bed knife, and flexible means extending from the bed knife to the lower edge of the mouth for partially closing said mouth.
- 10
- 15 5. A device of the character described in-

cluding upper and lower sections hinged together, a rotary knife mounted therein, the lower section having a cutout portion in the side and end walls thereof forming 20 an open mouth extending throughout the length of said lower section, an air pipe connected with said lower section substantially opposite the mouth, a movable bed knife for cooperating with the rotary knife, 25 and means connected with the bed knife and flexibly connected with the lower edge of the mouth for partially closing said mouth.

In testimony whereof we affix our signatures.

NOAH REINGOLD.
MEYER REINGOLD.
